JOSEPH KAYLOR, OF PITTSBURG, PENNSYLVANIA.

Letters Patent No. 87,780, dated March 16, 1869.

IMPROVEMENT IN BOLT-HEADING DIES.

The Schedule referred to in these Letters Patent and making part of the same.

To all whom it may concern:

Be it known that I, JOSEPH KAYLOR, of Pittsburgh, in the county of Allegheny, and State of Pennsylvania, have invented a new and useful Improvement in the Manufacture of Bolts; and I do hereby declare the following to be a full, clear, and exact description thereof, reference being had to the accompanying drawing, making a part of this specification, in which—

Figure 1 is a perspective view of a bolt-machine fitted with my improved dies, and illustrative of their operation;

Figure 2 is a vertical cross-section through the gripping-dies, just in the rear of the bottom of the recess in which the bolt-head is formed; and

Figures 3 to 6 are perspective views of various forms of dies illustrative of my improvement.

Like letters of reference indicate like parts of each.

My invention relates to the construction of dies for bolt-heading machines, and more particularly to that class of dies, which, by a second or subsequent stroke, when the partly-formed bolt-head is turned part way around, work in the flash, or fire, made at the first or a previous stroke; and

The nature of it consists in making the heading-side of the dies with a double recess, the inner recess being of the size and shape of the bolt-head to be made, and the outer recess being larger than the inner recess on two sides, which two sides may be either adjacent or opposite to each other, the two remaining sides of the larger recess being flush with the corresponding sides of the inner, or bolt-head recess. The flash, or fire, is then formed on the edges of the bolt-head, next the open sides of the outer recess, so that the bolt-head being turned part way around for another stroke of the dies, the flash, or fire, will come next the sides of the outer recess, which are flush with the sides of the inner, or bolt-head recess, by which, and the heading, such flash, or fire, will be worked into the head.

To enable others skilled in the art to make and use my invention, I will proceed to describe its construction and mode of operation.

A is the frame of the machine;

B, the cam-shaft; and

C and C', cams, which are so set that the one, C', shall operate a little in advance of the other, C.

D is a stationary, and

D', a movable die-block, though both may be movable, if so preferred.

In these are set the gripping or side-dies d d'.

b is a heading-die, actuated by the cam C, through the stem b'.

j' is a like stem, which, operated by the cam C', gives the die-block D' and its die d' a forward stroke.

The die d' receives its return-stroke from a spring, g, and the header b is carried back by a like spring or other equivalent device, attached at any suitable point.

A' is an aperture in the frame, through which the bolt-rod, properly heated, is fed in.

The gripping-dies d d have the usual cavities, i, for the shank of the bolt.

In the several figures, e represents the inner, or bolt-head recess, half of it being made in each die, and in such a way that when the two dies come together, the inner recess so formed will give the proper cavity for a square bolt-head, as in figs. 1, 2, and 5, or a hexagonal bolt-head; as in fig. 3, or a T-head, as in fig. 6.

The half recess e in each die may be triangular, as in figs. 1 and 2, or rectangular, as in fig. 5.

An outer recess, e, is made in each die, the bottom of which is even with the top of the inner recess.

This recess e, or these recesses, are so made, that when the dies come together, an open space shall be left on at least two sides of the inner, or bolt-head recess c.

Such open sides may be adjacent to each other, and must be for T-head bolts, as in fig. 6, or they be opposite to each other, as in figs. 1, 2, 3, and 5.

The remaining sides of the outer cavity e are made flush, or even with the corresponding sides of the inner cavity c, as in all the figures except fig. 4, which shows a pair of dies with the outer recess e open, or enlarged on all sides, around the inner recess, or cavity c.

The header b is made of the size and shape to fit the outer, or larger recess e, and receives, from its cam, C, a stroke such as to bring its working-face, in heading a bolt, even with the top of the inner cavity c.

The face of this header b may be concave or have other desirable form, so as to make the top face of the bolt-head flat, convex, or otherwise, at pleasure.

The rod from which the bolt is to be formed, being heated, is introduced, between the gripping-dies d d', through the aperture A' sufficiently far, so that enough metal shall project through to form a bolt-head of the required size. The gripping-dies then catch the rod by the semi-cylindrical cavities, when the header b comes forward, strikes the end of the rod, and upsets a head in the lower recess c. The dies then open; the bolt, if square, is turned one-fourth way around; if hexagonal, one-sixth; if rectangular, or of T-shape, one-half, &c.; and the dies, by another stroke, work into the head any flash, or fire that may have been formed on the head at the previous stroke. The bolt being cut off, the bar is then complete, and the operation is repeated.

It will be observed, that with the construction of dies shown and described, any part of the bolt-head on which a flash, or fire, can be formed at the first stroke of the dies, will, on the turning of the bolt as described, at the next succeeding stroke of the dies, come against a solid face of some one of the dies. This will prove the case in reference to all, except the T-head bolt, shown in fig. 5, and in that the only exception will be as to the flash, or fire, if any, which may be formed at the "part" of the rolls. But, in all the dies shown, the flash, or fire, will be formed solely, if not exclusively, on the edges of the upper face of the bolt-head, which are next the enlarged, or open part of the upper recess e,

and every flash, or fire there formed, will, on the turning of the bolt, come against the opposite faces of the upper recess, which are flush with the corresponding faces of the lower recess *c*.

I have described the outer recess as being enlarged, or open on two sides of the inner recess, but in dies for making a hexagon bolt-head, as in fig. 3, the outer recess should be open, or enlarged around half the periphery of such recess.

I am aware that it is not new to turn a partly-formed bolt one-quarter way around to work in the flash, or fire; also, that bolt-heading dies have been so made that a flash, or fire, formed on any part of the head, would, at a subsequent stroke of the dies, on the head being turned one-quarter of the way around, come in con-

tact with a solid face of one of the dies. I, hence, do not claim these features as applied broadly to bolt-heading dies of substantially a different construction from that above described; but

What I do claim as my invention, and desire to secure by Letters Patent, is—

The construction of dies *d d'* for bolt-heading machines, having recesses *c e*, made and used substantially as above set forth.

In testimony whereof, I, the said JOSEPH KAYLOR, have hereunto set my hand.

JOSEPH KAYLOR.
